R. W. CHARLTON

CONTENTS EJECTOR FOR RECEPTACLES

Filed May 18, 1921

UNITED STATES PATENT OFFICE.

ROBERT W. CHARLTON, OF PINEVILLE, LOUISIANA, ASSIGNOR OF ONE-HALF TO
AUGUST F. KLUMPP, OF PINEVILLE, LOUISIANA.

CONTENTS EJECTOR FOR RECEPTACLES.

Application filed May 18, 1921. Serial No. 470,596.

To all whom it may concern:

Be it known that I, ROBERT W. CHARLTON, a citizen of the United States, residing at Pineville, in the parish of Rapides and State of Louisiana, have invented certain new and useful Improvements in Contents Ejectors for Receptacles, of which the following is a specification.

My invention relates to contents ejectors for receptacles and in particular to improvements in the means associated with the ordinary flat tin pocket receptacle for granulated smoking tobacco for lifting the unused contents thereof to the open end of the receptacle. It has been proposed heretofore to provide means for this purpose, and my invention consists in means associated with the lifting means for locking it in predetermined position.

20 In one embodiment of the invention the locking means is adapted for manual manipulation to lock or release the lifting means, whereas in another embodiment thereof it is automatic in its operation.

25 The above and such other objects as may hereinafter appear are attained by the novel construction, combination and arrangement of parts to be hereinafter specifically described and claimed.

30 Reference will now be had to the accompanying drawings forming a part of this specification, wherein:

Figure 1 is a perspective view of an ordinary flat tin tobacco can showing one embodiment of my invention applied thereto.

35 Figure 2 is a transverse vertical sectional view of the can.

Figure 3 is a longitudinal vertical sectional view taken on the line 3-3 of Figure 40 2 and looking in the direction of the arrows.

Figure 4 is a horizontal sectional view taken on the line 4-4 of Figure 3 and looking in the direction of the arrows.

Figure 5 is a perspective view of the locking member employed in the construction shown in Figures 1 to 4 inclusive.

Figure 6 is a fragmentary vertical sectional view on an enlarged scale showing a different form of locking element.

50 Figure 7 is a view taken at right angles to Figure 6 showing the locking member and its retaining strip.

Throughout the following detailed description and on the several figures of the

drawing, similar parts are referred to by 55 like reference characters.

Referring to the drawings, the reference numeral 1 designates an ordinary flat tin tobacco receptacle having a hinged lid 2 and 3 the paper container for the tobacco shown 60 slightly raised in Figures 1 and 2. The lifting means consists of a narrow tape 4 of paper or other suitable material having one end fastened to the rear side of the receptacle near the top thereof, the receptacle having slits 5 formed therein through which the end of the tape is passed from the inside outwardly through the top slit and then inwardly through the lower slit, the friction 65 between the end of the tape and the edges of the narrow strip of metal 6 between the slits being sufficient after the tape is folded downwardly inside the receptacle to hold the end of the tape securely against pulling out of the slits. This frictional engagement 70 can be made more secure if desired by pressing the strip 6 slightly outwardly after the end of the tape has been passed through the slits 5. The tape 4 passes down inside the receptacle beneath the lower end of the container 3 and then up to the top of the receptacle, having its free end portion bent over the top edge of the front side of the receptacle to form a small tab which may be 75 taken hold of to lift the container 3 to bring the unused tobacco therein to the top of the receptacle. When the cover 2 is closed the edge thereof may be used to shear or cut off excess of tape as the container 3 is 80 raised higher and higher in the receptacle.

85 Of course it will be understood that when the container 3 is raised the portion thereof projecting above the end of the receptacle may be torn off, the top edge of the receptacle being used as a shear for this purpose. 90 The construction so far described is old and no claim is made thereto, my invention residing in the means for locking the tape in predetermined position.

95 The embodiment of the invention wherein the locking means is manually manipulated is shown in Figures 1 to 5, inclusive. Referring to Figures 1 to 4, inclusive, it will be seen that the front side of the receptacle is provided near the top thereof and opposite the slits 5 with an outwardly bulged portion 8 at the opposite ends of which openings 9 are provided. The locking member 10 is 100 105

2
shown in Figure 5 and is preferably made in a single piece from wire and has its ends 11 and 12 bent at right angles to the body portion. The end portions 13 of the body portion are in axial alignment to form the journals of the locking member, the portion 14 between the end portions 13 being offset to form a cam or locking portion. The cam portion 14 is arranged in the recess 5 formed by the bulged portion 8 of the receptacle, the journal portions 13 extending through the openings 9 and the tape 4 passing between the cam portion 14 and the rear face of the front side of the receptacle. The ends 11 and 12 of the member 10 are located at the outer face of the front side of the receptacle and the end 12 being the longer of the two constitutes a handle by means of which to manipulate the locking member. 10 When the locking member is rotated on its journals 13 until the end portions 11 and 12 engage flat against the side of the receptacle and extend downwardly the cam portion 14 clamps the tape firmly against the 15 rear face of the front side of the receptacle so that the container 3 cannot be raised by pulling on the tab 7. However, when the locking member is rotated in the reverse direction until the ends 11 and 12 engage 20 the side of the receptacle and extend upwardly the cam portion 14 is moved away from the rear face of the front side of the receptacle thus releasing the tape so that the container 3 may be raised by pulling on the 25 tab 7. When the locking member 10 is turned to locking position with the ends 11 and 12 resting against the outer face of the receptacle and pointing downwardly, these ends are apt to engage and stick in the 30 cloth when placing the receptacle in the pocket or when removing it therefrom. In order to prevent this the side of the receptacle is bulged outwardly just below the 35 positions occupied by the ends 11 and 12 as indicated at 15 in Figure 1.

Figures 6 and 7 show a construction somewhat similar to that shown in Figures 1 to 5, inclusive, but in which the locking member is automatic in its operation. In this 40 embodiment of the invention the locking member is a straight piece of wire 16 having a roughened surface. The side of the receptacle is bulged outwardly as before as indicated by the reference numeral 17 to 45 form a recess to receive the locking member and the latter is retained in the recess by a strip of metal 18 secured to the rear face of the side of the receptacle. The tape can 50 pass either between the locking member 16 and the rear face of the side of the receptacle or between the locking member and the strip 18. Pulling on the tape tends to lift 55 the locking member 16 into the deep portion of the recess formed between the bulged portion 17 and the strip 18 so that there is

no difficulty in raising the container 3, but any tendency of the latter to move downwardly causes the locking member 16 to jam in the shallow portion of the recess as indicated clearly in Figure 6 and thus clamp 70 the tape either against the side of the receptacle or against the strip 18.

Having thus described my invention, what I claim as new and desire to secure by Letters Patent is:

1. The combination with a receptacle of a carton therein, means passing beneath the carton for lifting the same, and means separate from the lifting means arranged to be positively actuated by a return movement 80 thereof for locking said lifting means in contact with the receptacle in a predetermined elevated position of the carton.

2. The combination with a receptacle, a carton therein, and means passing beneath 85 the carton for lifting the same, comprising a member slidably relative to a wall of said receptacle, of clamping means supported in a recess formed by bulging outward a portion of said wall and movable to clamp said 90 slidably member against the wall of the receptacle to lock said member in a predetermined elevated position.

3. The combination with a receptacle and means for lifting the contents thereof, comprising a member slidable with respect to a wall of said receptacle, of a locking member having a cam portion arranged in a recess formed by bulging outwardly a portion of said wall, said member having an end portion 95 extending to the outside of said receptacle whereby to move said member to cause said cam portion to clamp said slidable member against said wall.

4. In combination, a receptacle having a 105 mouth at its upper end, a member slidable with respect to a wall of said receptacle and adapted to lift the contents thereof, said wall having an outwardly bulged portion, and a locking member having a cam portion 110 located in the recess formed by said outwardly bulged portion and portions at the ends of said cam portion journaled in openings in said wall at the ends of said outwardly bulged portion, said member having 115 means extending to the exterior of said receptacle whereby to move said member to cause said cam portion to clamp said slid- able member against said wall.

5. In combination, a receptacle having a 120 member slidable with respect to a wall of said receptacle for lifting the contents of the receptacle to the mouth thereof, said wall having an outwardly bulged portion, and a locking member consisting of a single piece 125 of wire having journal portions extending through openings in said wall at the ends of said outwardly bulged portion, an offset portion between said journal portions and located in the recess formed by said out- 130

wardly bulged portion, and end portions extending outwardly from said journal portions, one of said end portions constituting a handle whereby to turn said member to 5 cause said offset portion to clamp said slideable member against said wall.

6. The combination with a receptacle and a contents package therein, of means for lifting the contents package comprising a 10 flexible strip having one end thereof attached to the receptacle at one side and passing beneath the contents package and out of

the mouth of the receptacle at the other side, and a positively actuated clamp mounted on the last named side of the receptacle in 15 position to cooperate with the flexible strip to clamp and lock the latter against the wall of the receptacle to prevent returning movement after the strip is pulled upwardly from time to time to lift the contents package as the contents thereof are removed. 20

In testimony whereof I affix my signature.

ROBERT W. CHARLTON.
